(57) **CLAIM**

An ornamental design for a hanger clip for stairway spindles and balusters, as shown and described.

DESCRIPTION

FIG. 1 is a front right perspective view of the hanger clip for stairways spindles & balusters.

FIG. 2 is a back right perspective, bottom view of the hanger clip for the stairway spindles and balusters, as disclosed in FIG. 1;

FIG. 3 is a top view of the hanger clip for stairway spindles and balusters, as disclosed in FIG. 1;

FIG. 4 is a left side view of the hanger clip for stairway spindles and balusters, as disclosed in FIG. 1;

FIG. 5 is a front view of the hanger clip for stairway spindles and balusters, as disclosed in FIG. 1;

FIG. 6 is a right side view of the hanger clip for stairway spindles and balusters, as disclosed in FIG. 1;

FIG. 7 is a bottom view of the hanger clip for stairway spindles and balusters, as disclosed in FIG. 1;

FIG. 8 is a back or rear view of the hanger clip for stairway spindles and balusters, as disclosed in FIG. 1;

FIG. 9 is a top view illustrating a second embodiment of the hanger clip for stairway spindles and balusters;

FIG. 10 is a perspective view of the second embodiment of the hanger clip for stairway spindles and balusters, as disclosed in FIG. 9;

FIG. 11 is a top view illustrating a third embodiment of the hanger clip for stairway spindles and balusters;

FIG. 12 is a perspective view of the third embodiment of the hanger clip for stairway spindles and balusters;

FIG. 13 is a bottom view, front left perspective of the hanger clip for stairway spindles and balusters, as disclosed in FIG. 1;

FIG. 14 is a perspective view of the hanger clip for stairway spindles and balusters, as disclosed in FIG. 1; shown illustrated on an unclaimed square spindle or baluster; and,

FIG. 15 is a perspective view of the hanger clip for stairway spindles and balusters, as disclosed in FIG. 1; shown illustrated on an unclaimed circular spindle or baluster.

My new design for a "hanger clip" for stairway spindles & balusters is designed to allow stairway spindles & balusters to be decorated, highlighted or showcased in addition to the railings & bannisters. Instead of having to use nails, glue, tape, twine or cable ties to attach or hold greeting cards, holiday stockings, lighting, and other seasonal decorations to the spindles or balusters, my design allows for a quick attachment & detachment on circular, square or diamond shaped spindles or balusters at any height or placement. Event and Wedding planners could also use these "hanger clips" for their temporary decorations at churches, homes or

(Continued)

halls were events are hosted and no permanent trace or damage can be left behind at the conclusion of the event or party. It can be used on stairway spindles & balusters, chairs, pipes, or similarly shaped structures in either interior or exterior applications.
